Alva L. Kitselman, Inventor
By his Attorneys,

C. Snow & Co.

UNITED STATES PATENT OFFICE.

ALVA L. KITSELMAN, OF RIDGEVILLE, INDIANA.

WOVEN-WIRE FENCING.

SPECIFICATION forming part of Letters Patent No. 606,421, dated June 28, 1898.

Application filed January 26, 1898. Serial No. 668,045. (No model.)

To all whom it may concern:

Be it known that I, ALVA L. KITSELMAN, a citizen of the United States, residing at Ridgeville, in the county of Randolph and State 5 of Indiana, have invented a new and useful Woven-Wire Fencing, of which the following is a specification.

This invention relates to woven-wire fencing; and it has for its object to provide an 10 improved fencing of this character which shall be durable and strong and at the same time present an ornamental appearance to render the same especially useful as an ornamental wire fence.

15 The invention also contemplates a wire fence or fencing so constructed that the same will readily contract and expand according to changes in temperature without impairing the rigidity of the fence or the design thereof.

20 With these and other objects in view, which will readily appear as the nature of the invention is better understood, the same consists in the novel construction, combination, and arrangement of parts hereinafter more fully 25 described, illustrated, and claimed.

In the drawings, Figure 1 is a plan view or elevation of a section of wire fence constructed in accordance with the present invention. Fig. 2 is a cross-sectional view on the line 2 2 30 of Fig. 1.

In constructing the wire fence contemplated by the present invention a series of parallel warp-wires 1 are employed. These warp-wires extend longitudinally of the fence and are 35 provided with long pitch-coils 2, which produce in elevation a longitudinal series of regularly-curved symmetrical crimps or bends. The warp-wires of this particular construction form a necessary part of the present invention to insure a regular contraction and 40 expansion of the entire fence fabric without any strain or distortion thereof. The said coiled warp-wires 1 are the same form of wires which are coiled by the use of the wire-coiling 45 machine disclosed in the pending application of William H. Jones, Serial No. 641,845, filed June 22, 1897, and are used in conjunction with the diamond-mesh fabric woven by the type of fence-weaving machine set forth in 50 my former patent, No. 504,984, issued September 12, 1893.

The diamond-mesh fabric used in conjunc-

tion with the longitudinal warp-wires 1 is formed by twisting together the weft-wires 3 at their points of intersection, as at 4. At 55 the points of intersection of the weft-wires 3 the twisted portions 4 of such wires are closely wrapped about the warp-wires 1 to provide a firm connection between the weft-wires and the warp-wires and thereby insuring a rigid 60 structure of fence, while at the same time producing longitudinally - alined diamond meshes which are bisected by the separate portions of the coiled wires 1. In this connection it is to be further observed that the 65 greatest width of the diamond-shaped meshes 5 of the fabric is disposed lengthwise of the fencing in order that said meshes can freely widen out and contract simultaneously with the contraction and expansion of the coiled 70 wires extending across the same.

By reason of arranging the diamond-shaped meshes in the manner described in connection with the coiled wires extending across such meshes it will be obvious that as the 75 meshes and coiled wires of the fabric expand and contract such expansion and contraction will not loosen or otherwise affect the rigidity of the fence, nor will it distort the design thereof. 80

Having thus described my invention, what I claim, and desire to secure by Letters Patent, is—

A woven-wire fence comprising a plurality of parallel warp-wires extending longitudinally of the fence and regularly coiled throughout their entire length, and weft-wires twisted together at their points of intersection to produce diamond-shaped meshes having their greatest width disposed lengthwise 85 of the fence, the twisted portions of the intersecting weft-wires being closely wrapped about a coil of said warp-wires, which latter bisect the diamond-shaped meshes and contract and expand therewith without becoming 90 loose at their points of connection with the weft-wires, substantially as set forth. 95

In testimony that I claim the foregoing as my own I have hereto affixed my signature in the presence of two witnesses.

ALVA L. KITSELMAN.
